E. K. ANDERSON

FURNACE

Filed Jan. 23, 1924

INVENTOR
E.K. ANDERSON
By E.B. Birkenbeul
ATTORNEY

UNITED STATES PATENT OFFICE.

ERNEST K. ANDERSON, OF PORTLAND, OREGON.

FURNACE.

Application filed January 23, 1924. Serial No. 687,945.

To all whom it may concern:

Be it hereby known that I, ERNEST K. ANDERSON, a citizen of the United States, and a resident of Portland, in the county of Multnomah and State of Oregon, have invented a new and useful Furnace, of which the following is a specification.

This invention relates more particularly to furnaces for warming air with gas or liquid fuels.

An object of my invention is the construction of a warm air furnace in which the air space is kept as large as possible for a given outside dimension of a furnace.

15 A second object is to so construct the furnace that the condensation can be gathered and drawn off without maintaining a sufficiently high stack temperature to carry the moisture off with the burned gases.

20 A third object is to reduce the corrosive effect of the moisture which is formed when burning hydro carbons by draining the condensed moisture off as rapidly as it is formed, and by rendering it possible to keep

25 the metal in the furnace at a lower temperature and therefore less subject to corrosive action than is ordinarily possible.

A fourth object is to so construct the air flues that they cannot become air-bound.

30 A fifth object is the elimination of dead air space above the fire box by inclining the tubes towards the center of the furnace.

A sixth object is to avoid the use of a top or head over the combustion chamber 35 from which it is difficult to conduct the heat, which causes them to burn out very quickly.

I accomplish these results in the manner set forth in the following specification and 40 illustrated in the accompanying drawing, in which:—

Figure 1 is a front elevation of the furnace with its outer casing cut away in section and with portions broken away for 45 clearness. Figure 2 is a transverse section along the line 2—2 in Figure 1. Figure 3 is a horizontal section along the line 3—3 in Figure 1.

Similar numbers of reference refer to the 50 same parts throughout the several views.

Referring in detail to the drawing, I have employed a fire brick or asbestos fire box 10 in the construction of my furnace whose arched top 11 is provided with openings 12^A to permit the burning gas to escape into the air flue compartment. The air flues

12 are placed in double rows which incline toward the center of the furnace. The flues 12 are illustrated as square but may be of any shape other than round, for reasons 60 which will be explained later.

Each of the flues 12 is provided at both ends with flared spacing flanges 13 which hold the flues a fixed distance apart. The flanges 13, when assembled, form the 65 equivalent of the sheet through which tubes are ordinarily passed.

An enclosing sheet of metal forms the sides 14, the front 15 and the back 15^A. The front 15 is provided with out-turned flanges 70 16. A base having vertical sides 17 supports the flue compartment over the fire box 10. An outer wall 18 ordinarily covered with a nonconductor of heat (not shown) and having a cover 19 to which are joined 75 distributing pipes 20 is placed over the furnace and is attached to the out-turned flanges 16 in the most convenient manner.

The front wall 21 is provided with a door 22 hinged to a casting 23 and is notched 80 at its lower end to receive the burner pipe 24 which rests in a notch in the casing 25. Baffle plates 26 separate the flues of each pair of rows, and corner outlets 27 convey the burned gases to the smoke flue 28 by 85 means of the back flues 29.

Drain pipes 30 carry the condensation through a hole in the floor into the earth where it can be absorbed as rapidly as 90 formed. In some cases it may be convenient to connect these drain pipes to sewer systems.

The operation of my device is as follows: Gas or liquid fuel is burned in the fire box 10 and the heat passes upward through the 95 openings 12^A against and between the inner rows of flues 12, thence over the baffles 26, thence downward around the outer rows of flues 12, and thence out through the flues 27, 29 and 28.

The object in avoiding circular flues is to increase the air handling capacity of the furnace by increasing the area of the flues and by preventing the retarding of air flow through the tubes, as is commonly the case 100 when heat radiates to or from the center of a circular flue.

It must be understood that when hydro carbon gases are burned that the by-product is largely water since the hydrogen in the 110 gas unites with the oxygen of the air during combustion, and this water containing traces

of sulphur in the form of sulphur dioxide forms liquids which readily attack the metal parts of furnaces.

It will be seen that in my furnace this liquid is drawn off as rapidly as it is formed. The practice, therefore, has been to maintain a relatively high stack temperature, and even to burn gas jets in flues for the purpose of carrying the moisture out by way of the chimneys. I prefer to carry off this moisture as soon as it is formed and to avail myself of the economy naturally accompanying the reduction in stack temperature.

Another advantage which occurs in my furnace arises from the fact that the air which must pass through the furnace is not heated to such a high degree and therefore does not have such a low degree of humidity as is the case where hot air is given off by the furnace, thereby making it a real warm air furnace.

Another advantage arising from the construction above described is the reduction in the amount of seams in the furnace, since the usual head or sheet through which the air flues must pass is entirely omitted and the flue flanges 13 are themselves joined together instead of being joined to another sheet.

I am aware that many forms of warm air furnaces have been constructed in the past, I therefore do not claim same broadly but intend to cover such forms and modifications as fall fairly within the appended claims.

I claim:

1. A furnace having a fire box with openings on its upper side; rows of square open flare-ended air flues on opposite sides of said fire box, said flues converging at their upper ends and meeting at the center of said furnace; a wall formed around said flues adapted to confine burning gases from said combustion against the sides of said flues; an

outlet means in said walls for exhausting said gases, said flues being free to receive air at their lower ends and discharge same from their upper ends. 45

2. A gas furnace having, in combination, a combustion chamber; an air flue chamber from said combustion chamber; a plurality 50 of flare-ended square air flues passing upwardly across said combustion chamber and meeting at the top in a manner to avoid the use of a large top over the combustion chamber; and means for withdrawing the by-product water which may condense on the bottom of said flue chamber without causing same to pass out of the smoke stack or to be re-evaporated into the air passages. 55

3. A gas furnace having, in combination, a combustion chamber; a pair of rows of square-ended flared air flues on each side of said combustion chamber; a wall surrounding the sides of said flues and said combustion chamber, said flues converging at their 65 upper ends toward the center of said furnace; drains for carrying off the liquid by-products of combustion; an outer casing completely surrounding said flue compartment; and smoke flues for carrying gases 70 from around said flues out through said outer casing and into a smoke stack.

4. A gas furnace having, in combination, a combustion chamber; a double row of square air flues on each side of said combustion chamber, each of the flues having flared 75 ends, said flared ends being hermetically joined to the adjacent flared ends; baffle plates between the rows of each pair of rows of flues; a wall around said flues with an outer casing separated from said wall; smoke flues passing from said flue enclosing wall through said outer casing; and means for draining the liquid products of combustion from said flues. 80
